ROTOR WITH SPACED LARGE SHREDDING BLADES COOPERATING WITH TOOTHED STATOR.

Robert B. Honeyman, Portland, Oreg., assignor to Morden Machines Company, Portland, Oreg., a corporation of Oregon

Application July 29, 1957, Serial No. 674,751

4 Claims. (Cl. 241—260)

The present invention relates to devices for the shredding and treating of fibrous material, such as old paper stock and dried pulp sheets, in order to render the material in proper condition for use in paper manufacture. In the proper preparation of such material for use in the manufacture of paper and related products, the material must be broken up, shredded and slushed, and the fibers in the material should be subjected to a certain amount of refining action.

The invention relates specifically to the particular type of machine for shredding and treating fibrous material to be used in paper manufacture as described in U. S. Patent No. 2,654,294 to C. W. Morden, issued under date of October 6, 1953, and entitled "Pulp Shredding and Treating Machine," and reference should be made to this earlier patent for a full understanding of the present invention.

In the device of the above mentioned patent, No. 2,654,294, the shredding and treating of the fibrous pulp material are accomplished by means of a rotor operating in conjunction with a stationary impingement ring, the stationary ring having a conically-shaped attritioning surface, the rotor having peripheral blades which move over this stationary attritioning surface, and the under sides of the rotor blades so located as to lie in a conical surface capable of mating with the attritioning surface of the stationary ring.

The blades of the rotor, in the device of the above mentioned patent, are designed to serve the double purpose of impinging material against the conical surface of the stationary ring and of cooperating with the stationary ring in subjecting the fibrous material to an attritioning action between the rotating blades and the stationary ring surface, and, under optimum conditions, this double purpose is accomplished to a large extent by the device described in the patent. In such a device the blades on the rotating rotor must of necessity be fairly close together in order to perform the desired attritioning action in the short length of time during which the fibrous material is in contact with the conical or attritioning surface of the stationary ring, and in consequence the pieces of the fibrous material must first of all be small enough to pass down between the blades of the rotor so as to reach the attritioning surface on the stationary ring. However, when the material to be treated includes a considerable amount of moderately large pieces or slabs of such fibrous material, as is frequently the case, these larger pieces or slabs will collect on the rotor, or bridge over the rotor, temporarily until they are sufficiently broken up, and during this interval they act as a block to the smaller particles of material and act as an impediment in the proper performance of the intended function of the machine. It has been found that this condition may exist to such an extent temporarily that the circulation set up through the blades of the rotor will be reduced largely to water and consequently during such temporary interval the machine operation is far from being efficient.

2

Various attempts have been made to achieve more efficient operation of the machine by relieving such conditions and reducing the time required for the breaking up of such larger pieces of fibrous material, including increasing the rotor speed. However, these have not proved a satisfactory solution to the problem, and furthermore a considerable increase in the speed at which the rotor is driven results in the use of a greater amount of power at increased ratio of power consumption to rotor speed.

10 An object of the present invention accordingly is to facilitate and hasten the breaking up of larger pieces of slabs of material, in a pulp shredding and treating machine of the type mentioned, without requiring any very extensive changes in the overall construction of such machine, and without even changing the number or spacing of the rotor blades which are considered most desirable for the particular machine size or given installation, and without varying the important and necessary cooperation between rotor blades and the stationary attritioning ring.

15 A related object of the present invention is to provide an improved rotor in such machine which will produce greater agitation of the fibrous material in the tank with a minimum increase of power required, and also make possible an improved preliminary slushing action on the fibrous material, and consequently promote a more effective circulation of the material through the rotor blades and over the attritioning face of the stationary ring.

These objects and other incidental advantages are attained by changing some of the rotor blades to make them extend up beyond the top edges of a majority of the blades on the rotor so as to encounter the larger pieces or bundles of fibrous material before these larger pieces are able to collect to such extent as to block the passage of material down between the rotor blades to the attritioning ring, but without making any change in the size or position of the under sides of the higher blades or any changes in the spacing between the blades, and by other specific construction features as hereinafter mentioned.

20 This improved rotor construction, or rotor blade construction, of the present invention, will be described and explained briefly with reference to the accompanying drawings.

In the drawings:

25 Figure 1 is an elevation of the improved rotor shown in its operation relationship with the stationary attritioning ring of the pulp shredding and treating machine;

30 Figure 2 is a corresponding elevation of the stationary ring by itself, for the purpose of making the other figures clearer;

35 Figure 3 is a section through the improved rotor and stationary ring taken on the line 3—3 of Figure 1;

40 Figure 4 is a fragmentary section through the rotor without the stationary attritioning ring, taken on the line 4—4 of Figure 1, showing one of the standard blades of the rotor in elevation;

45 Figure 5 is a fragmentary section through the rotor without the attritioning ring, taken on line 5—5 of Figure 1, showing one of the special blades of the rotor in side elevation;

50 Figure 6 is an outer end view of one of the standard blades on the rotor taken on the line indicated at 6—6 in Figure 1;

55 Figure 7 is a corresponding end view, drawn to the same scale as Figure 6, of the outer end of one of the special blades on the rotor taken on the line indicated at 7—7 in Figure 1;

60 Figure 8 is a fragmentary side elevation of the rotor taken on line 8—8 of Figure 1, with the stationary attritioning ring omitted for the sake of clarity, showing one of the standard blades; and

65 Figure 9 is a similar fragmentary side elevation of the

rotor taken on line 9—9 of Figure 1 showing one of the special blades.

Referring first to Figures 1 and 3, the rotor, indicated as a whole by the reference character 10, has a front, substantially conical, or dome-shaped, face with a series of peripheral blades. Preferably, but not necessarily, the rotor comprises a main central integral casting 11 (Figure 3) having a rearwardly-extending central boss 12 formed with a tapered bore to accommodate the tapered end of the driven rotor shaft 13, to which the rotor is keyed, and having a dome-shaped nut 14, secured in place on the end of the rotor shaft and in the body portion 11, which completes the conical or dome-shaped rotor surface. Also preferably the blades of the rotor are cast integral with an annular base or ring 15 which is then mounted in a peripheral recess 16 in the main casting 11 and secured in place on the rotor body by suitable screws.

The composite rotor preferably, but not necessarily, is mounted in the side of the tank containing the fibrous material to be treated, as described in U. S. Patent No. 2,654,294, and thus rotates in a vertical plane, with the conical or dome-shaped front face of the rotor facing the interior of the tank. A stationary impingement and attritioning ring 17 surrounds the rotor and is secured to a housing which in turn is mounted to the wall of the tank, a portion of the housing being indicated at 18 in Figure 3 and a portion of the tank being indicated at 18'. This stationary ring 17 has a frusto-conical attritioning surface 19 (see also Figure 2) which is inclined at an angle (preferably of approximately 45°) with respect to the plane of rotation of the rotor. The attritioning surface is formed with a series of radially-extending rectangular grooves 20, thus forming radial teeth or attritioning bars between the grooves of the attritioning surface 19.

The rotor blades extend beyond the rotor periphery to the periphery of the attritioning surface 19 of the stationary ring, and the under sides of the blades lie in a frusto-conical surface capable of mating with the attritioning surface 19 of the stationary ring. Means (not shown) is provided for adjusting the rotor shaft 13 to a limited extent in an axial direction and thereby adjusting the clearance between the blades and the attritioning surface 19 of the stationary ring.

The rotor blades, instead of being all the same size, as has been customary heretofore, are of two sizes, a few of the blades having a greater height than the others. The blades, however, are all of the same width and the spacing is the same between all the blades. Thus, in the rotor shown in Figure 1 as an example, there are twenty-seven blades. Three of these blades, indicated by the reference character 21, are higher than the others or the standard blades 22. The higher blades 21 of the set are spaced equal distances from each other, thus, in this instance being spaced 120° apart. The difference in height between the higher blades 21 and the other blades 22 is shown clearly in Figures 3, 4 and 5.

The under sides of all the blades are identical in size and shape. The under side of each blade has an open central channel 23 which extends to the outer end of the blade. Thus all the blades are prong-like, with the under side of each blade having spaced surfaces, and as these prong-like blades move closely over the attritioning surface 19 of the stationary ring they perform a desired treating action on the pulp fibers of the fibrous material which has been impinged against the stationary ring by the rotation of the rotor.

As apparent from Figure 1, all the rotor blades extend obliquely away from the direction of rotation of the rotor, the direction of rotation being clockwise as viewed in Figure 1 and as indicated by the arrow "x." Also the leading face of each blade, that is the lateral side of the blade facing in the direction of rotation of the rotor, extends in a plane sloping obliquely from the plane of

rotation of the rotor, while the trailing face or other lateral side of each blade extends in a plane substantially perpendicular to the plane of rotation of the rotor. Thus the leading face 24 (Figures 7 and 9) of each of the higher blades 21, and the leading face 25 (Figures 6 and 8) of each of the standard blades 22 extends in a plane sloping obliquely with respect to the plane of rotation of the rotor while the trailing face 26 of each of the higher blades and the corresponding trailing face 27 of each of the standard blades extends in a plane substantially perpendicular to the plane of rotation of the rotor.

The top ridges 28 of the standard blades 22 (Figures 3 and 4) lie mostly in a frusto-conical surface sloping outwardly and upwardly with respect to the plane of rotation of the rotor, but sloping at a slightly less angle than the under side faces of the blades, as shown in Figure 3, and thus sloping at a slightly less angle than the attritioning surface of the stationary ring. Similarly the top ridges 29 of the higher blades 21 (Figures 3 and 5) lie in a frusto-conical surface which has approximately the same angularity with respect to the plane of rotation of the rotor as the frusto-conical surface containing the top ridges 28 of the standard blades.

The top ridges of all the blades begins at approximately the same radial distance from the axis of rotation of the rotor, starting from points located substantially on a common circle on the face of the rotor. The ridges 28 of the standard blades 22 have a greater extent of curvature at their start from the rotor face, as shown at 28' in Figure 4, than the ridges 29 of the higher blades 21, as shown at 29' in Figure 5.

The rotation of the rotor causes the fibrous material, engaged by the rotor blades, to be thrown outwardly from the rotor axis, but this results in a considerable portion of such engaged material being impinged against the frusto-conical surface of the stationary ring. The angularity of this ring surface (preferably approximately 45°) with the plane of rotation of the rotor causes the material impinged against this surface to be momentarily restrained, and during this time the material is subjected to an attritioning action between the under sides of the blades and the frusto-conical surface of the stationary ring with its radially extending bars and grooves. After this brief restraint and attritioning action the material is discharged peripherally by the rapidly moving blades for recirculation.

When pieces of material, small enough to pass down between the blades to the frusto-conical surface of the stationary ring, are too large to pass between the under sides of the blades and the ring surface, the obliquely-sloping leading faces of the blades urge such pieces upwardly and outwardly over the ring surface without forcing them in between the under sides of the blades and the ring. The impingement of these pieces against the ring surface will nevertheless tend to break them up or reduce their size, so that, after a sufficient amount of recirculation, the fibrous material from such pieces will finally receive the desired attritioning action between the blades and the frusto-conical surface of the stationary ring. Any foreign particles, such as tramp metal, which may inadvertently have been deposited in the tank with the fibrous material, will also be thrown off from the ring surface by the leading faces of the blades, thus reducing to a minimum the damage to the treating machine by such foreign particles.

As previously mentioned, one of the problems encountered with the operation of the pulp shredding and treating machine of U. S. Patent No. 2,654,294 has been the fact that, in many instances, larger slabs or masses of fibrous material, being too large to pass down between the rotor blades to the stationary ring, collect on or over the rotor, impeding the normal passage to the attritioning ring and retarding the proper circulation of material in

the tank. However, it has been found that the substitution of the higher blades 21 for some of the standard blades in the improved rotor prevents such condition developing and that pieces of the fibrous material which are too large to reach the attritioning ring at first are subjected to repeated impact by the higher blades with the result that they are either immediately broken up sufficiently by the higher blades to enable the reduced smaller particles to pass down to the ring, or else are thrown off from the rotor by the higher blades and in this way caused to be recirculated until such time as repeated impact by the higher blades will break up these larger pieces sufficiently. This recirculation of the larger pieces, caused by the higher blades, also has the added advantage of increasing the turbulence and circulation of all of the material in the tank and at the same time of keeping the passageways between the blades to the stationary ring open. Furthermore, this desirable increased turbulence and circulation of the material in the tank is attained without having to increase rotor speed and with only a minimum increase in power required.

Since spacing between all the blades is the same, and since the higher blades are no wider than the standard blades, the operation of the machine under optimum conditions, in which there would be no pieces of material too large to take the normal prescribed course to the frusto-conical attritioning surface of the stationary ring, is not rendered less efficient or modified in any way by the presence of the higher blades. However, since such optimum conditions seldom exist, and since generally there will be some pieces of material at the start of the machine operation which are too large to follow such normal course, the higher blades make it possible for these larger pieces to be controlled and handled, and consequently increase the overall operating efficiency of the machine.

For the purpose of this description the rotor has been illustrated as equipped with a total of twenty-seven blades, including three higher blades. While rotors with this number and arrangement of blades have proved very satisfactory and efficient, the invention is not to be considered as limited to a rotor having any particular number of blades or any particular number of higher blades. Thus, for example, under some conditions it might be preferred to have four of the higher blades on the rotor, and therefore spaced 90° apart, or more than four, or it might be sufficient to have only two of the higher blades. Similarly, of course, the number, and therefore the spacing, of all the blades on the rotor can be varied to suit different conditions of operation. It is essential, however, in the carrying out of this invention, that the number of the higher blades be considerably less than the number of the standard blades on the rotor, that the higher blades be spaced equidistant from each other, and preferably also that the under sides of the higher blades and of the standard blades be identical.

I claim:

1. In a pulp shredding and treating machine of the character described wherein a rotor is surrounded by a stationary ring having a frusto-conical attritioning surface and a plurality of blades on the rotor extend beyond the periphery of the rotor over the attritioning surface of the stationary ring and the under sides of the blades lie in a frusto-conical surface capable of mating with the attritioning surface of the stationary ring, the improvement in the rotor which includes having a few of said blades made of greater height than the other blades, but with the under sides of said higher blades lying in the same frusto-conical surface as the under sides of said other blades, said higher blades equally spaced from each other, the top edges of said higher blades extending in a frusto-conical surface inclined at an angle with the plane of rotation of the rotor and the top edges of all of said blades beginning on said rotor at points located substantially on a common circle concentric with the rotor axis, whereby,

5 with the rotation of said rotor, said higher blades will encounter larger pieces of the material being treated in said machine before said larger pieces reach said other blades on said rotor and thereby reduce the tendency of said larger pieces to impede the proper functioning of the machine.

2. In a pulp shredding and treating machine including a rotor surrounded by a stationary ring having a frusto-conical attritioning surface and a plurality of blades on the rotor extending beyond the periphery of the rotor over the attritioning surface of the stationary ring with the under sides of the blades lying in a frusto-conical surface capable of mating with the attritioning surface of the stationary ring, the improvement in the rotor which comprises having a few of said blades made of greater height than the other blades, but with the under sides of said higher blades lying in the same frusto-conical surface as the under sides of said other blades, the under sides of said higher blades being identical in shape and size with the under sides of said other blades, said higher blades equally spaced from each other, the top edges of said other blades extending in a frusto-conical surface inclined at a less angle with the plane of rotation of said rotor than the under sides of said blades, and the top edges of said higher blades extending in a frusto-conical surface inclined at substantially the same angle with said plane of rotation of the rotor as the top edges of said other blades, whereby, with the rotation of said rotor, said higher blades will encounter larger pieces of the material being treated in said machine before said larger pieces reach said other blades on said rotor and thereby reduce the tendency of said larger pieces to impede the proper functioning of the machine.

3. In a pulp shredding and treating machine wherein a rotor is surrounded by a stationary ring having a frusto-conical attritioning surface and a plurality of prong-like blades on the rotor extend beyond the rotor periphery over the attritioning surface of the stationary ring and the under sides of the blades lie in a frusto-conical surface capable of mating with the attritioning surface of the stationary ring, the improvement which comprises having a few of said blades made of greater height than the other blades, but with the under sides of said higher blades lying in the same frusto-conical surface as the under sides of said other blades, the under sides of said higher blades being identical in shape and size with the under sides of said other blades, all of said blades being equally spaced on the periphery of said rotor, said higher blades equally spaced from each other, the lateral side of each of said higher blades facing in the direction of rotation of said rotor extending in a plane oblique to the plane of rotation of said rotor, the opposite trailing side of each of said higher blades extending in a plane substantially perpendicular to said plane of rotation, the top edges of said higher blades extending in a frusto-conical surface inclined at an angle with said plane of rotation, and the top edges of all of said blades beginning on said rotor at points located substantially on a common circle concentric with the rotor axis, whereby, with the rotation of said rotor, said higher blades will encounter larger pieces of material being treated in said machine before said larger pieces reach said other blades on said rotor and thereby reduce the tendency of said larger pieces to impede the proper functioning of the machine.

4. In a pulp shredding and treating machine of the character described including a rotor surrounded by a stationary ring having a frusto-conical attritioning surface and a plurality of prong-like blades on the rotor extending beyond the periphery of the rotor over the attritioning surface of the stationary ring with the under sides of the blades lying in a frusto-conical surface capable of mating with the attritioning surface of the stationary ring, the improvement in the rotor which consists in having a few of said blades made of greater height than the other blades, but with the under sides of said higher blades lying

in the same frusto-conical surface as the under sides of said other blades, the under sides of said higher blades being identical in shape and size with the under sides of said other blades, all of said blades being equally spaced on the periphery of said rotor, said higher blades equally spaced from each other, the lateral side of each blade facing in the direction of rotation of said rotor extending in a plane oblique to the plane of rotation of said rotor, the opposite trailing side of each blade extending in a plane substantially perpendicular to said plane of rotation, the top edges of said other blades extending in a frusto-conical surface, and the top edges of said higher blades extending in a frusto-conical surface inclined at approximately the same angle with said plane of rotation as the

5 top edges of said other blades, and the top edges of all of said blades beginning on said rotor at points located substantially on a common circle concentric with the rotor axis, whereby, with the rotation of said rotor, said higher blades will encounter larger pieces of material being treated in said machine before said larger pieces reach said other blades on said rotor and thereby reduce the tendency of said larger pieces to impede the proper functioning of the machine.
